DESIGN FOR A WHISK BROOM

Clyde M. Poulson, Akron, Ohio

Application November 5, 1941, Serial No. 104,031

Term of patent 7 years

To all whom it may concern:

Be it known that I, Clyde M. Poulson, a citizen of the United States and a resident of Akron, in the county of Summit and State of Ohio, have invented a new, original, and ornamental Design for a Whisk Broom, of which the following is a specification, reference being had to the accompanying drawing, forming a part thereof.

In said drawing, Fig. 1 is a front elevational view of a whisk broom showing my design; Fig. 2 is a side elevational view thereof; and Fig. 3 is a top plan view thereof.

I claim:

The ornamental design for a whisk broom, substantially as shown.

CLYDE M. POULSON.
